Attorney—J. B. Felshin

ABSTRACT: The cylinder lock unit is mounted on the handle. It has adjustment features for rough as well as fine adjustment. A stud of appropriate length is used to take care of the thickness of the door. A setscrew on a locking cam takes care of micrometer adjustment for variations in door and gasket thickness. This handle and lock unit is for magnetic closure gasket-type refrigerator doors. The handle is fixed to the door by screws.

FIG. 7

J.B. Felskin
ATTORNEY

is a locking cam member 74. Said member 74 has an axially internally screwthreaded opening 75 receiving said opposite end of the stud. Said member 74 is formed with a radial screwthreaded opening 76 communicating with opening 75 to receive a setscrew 77 adapted to contact one of the surfaces 74 of the stud 71. The opening 75 is a blind opening. At the outer end of member 74 is a keeper engaging outwardly extending radial latch lug 78. When the key is turned to locking position lug 78 rotates into alignment with the inner side of arm 13c of the keeper 13.

The position of the locking cam 74 may be adjusted by loosening the setscrew 77 and turning the cam member 74 to its desired longitudinal position. Thereafter the setscrew 77 can again be tightened against surface 72 to hold the cam member 74 against rotation on the stud. It will be noted that the setscrew 77 is exposed when the door is open to permit fine adjustment of the cam member 74.

It will now be observed that the handle 18 is fixed to the door and that the locking of the door is affected by a key.

It will be noted furthermore that the lug 67 is of such angular extent that the cylinder can be rotated through an angle of 180°. Thus the arcuate groove 44 is of an angular extent which equals 180° plus the angular extent of the lug 67.

In FIGS. 5 to 8 there is shown a modified construction. In FIGS. 5 to 8 the handle 18 may be the same as in FIGS. 1 to 4. However, the handle is reversed so that the arm 18c is at the top and the arm 18b is at the bottom. The handle is attached to the door 10 in the same way as in FIGS. 1 to 4. The cylinder 45a is also the same as in FIGS. 1 to 4 except that instead of having a square stem 48 it is formed with a stem 80 which has a square portion 81 and a round portion 82. The stem 80 is formed with an axial-threaded opening 84 similar to the threaded opening 50.

Attached to the cylinder 45a is a member 86 having a cylindrical portion 86a. At one end of portion 86a is a cylindrical portion 87 of increased diameter received in the portion 43 of the through opening 40. Said portion 87 is formed with an arcuate radial lug 87a which is somewhat more than 90° in angular extent and is received in groove 44 of the handle. The angular extent of said lug 87a is such that the cylinder 45a can only move through an angle of 90°. Member 86 is formed at one end with an axial socket 88 of square cross section receiving the stem 80 of the cylinder 45a. Said member 86 is formed at its opposite end with an axial socket 89. It is furthermore formed with a smooth axial through opening 90 interconnecting the socket 89 with the socket 88. A screw 91 passes through the opening 90 and is screwed into the threaded opening 84 in the stem or extension 80 of the cylinder. The screw 91 has a head 92 which is located at the inner end of the socket 89.

Member 86 has a longitudinal crankpin extension 93 offset from the socket 89 and adjacent thereto.

Attached to door 10 by means of a pair of screws 94 is a locking bar housing 95. Said housing 95 comprises a wall 96 formed with a round opening 97 into which one end of member 86 projects for rotation. At the upper and lower ends of wall 96 are horizontal walls 98 interconnected by a wall 99 parallel to said wall 96. Wall 99 is not as wide as wall 96 leaving exposed shoulders 98a at walls 98. The screws 94 pass through smooth parallel openings 100 at the upper and lower ends of housing 95. Screws 94 are screwed into the door 10 as shown in FIG. 6.

The pin 93 projects into the slot 101 between walls 96, 99. A locking bar 102 of rectangular shape, is slidably received in slot 101. Said bar 102 is formed with a vertical slot 103 near one edge, into which slot the crankpin 93 projects. As the cylinder 45a is rotated through an angle of 90° in one direction the pin 93 slides the locking bar 20 in one direction to lock the door. The doorjamb has a keeper socket 105 to receive the

projected end of the locking bar. A keeper plate 106 attached to the doorjamb may have an opening 107 through which the locking bar passes. Upon rotating the cylinder 45a in an opposite direction, the locking bar is pulled clear of keeper plate 106 to allow the door to be opened.

A radial plane through the axis of member 86 and through the axis of pin 93 bisects the angle between the ends of lug 87a, so that as the cylinder is rotated through an angle of 90°, the lock bar will move horizontally, and the pin 93 will move from one side of a vertical plane through the axis of member 86 to the other side of said plane and said pin will move through an angle of 45° to each side of said plane.

It will thus be seen that there is provided an article in which the several objects of this invention are achieved, and which is well adapted to meet the conditions of practical use.

As possible embodiments might be made of the above invention, and as various changes might be made in the embodiments above set forth, it is to be understood that all matter herein set forth is to be interpreted as illustrative only.

I claim:

1. A door handle, means to fasten said handle to a door, a key-actuated cylinder rotatably and nonslidably mounted on said handle, a member, means to attach said member to said cylinder for rotation therewith and to hold said member to said cylinder against longitudinal sliding movement relative thereto, and locking means actuatable upon rotating said cylinder to lock the door to which the handle is attached, said attach means comprising a noncircular stem fixed on said cylinder, said member having a noncircular socket receiving said stem, and axial means on said member engaging said stem to hold said member and cylinder in axial alignment.

2. The combination of claim 1, and means to limit angular movement to said cylinder.

3. The combination of claim 2, said cylinder having a radial lug said means to limit, comprising said radial lug on said cylinder and said handle having an arcuate groove in which said lug is received.

4. A door handle, means to fasten said handle to a door, a key actuated cylinder rotatably and nonslidably mounted on said handle, a member, means to attach said member to said cylinder for rotation therewith and to hold said member to said cylinder against longitudinal sliding movement relative thereto, and locking means actuatable upon rotating said cylinder to lock the door to which the handle is attached, said locking means comprising a stud screwed at one end to said member, another member screwed to the other end of said stud, and a radial lug on said another member.

5. The combination of claim 4, said stud having one or more longitudinal flat faces, and setscrew means on said first mentioned member and on said another member adapted to engage a flat face of said stud.

6. The combination of claim 1, said locking means comprising an axial stud screwed to said member and another member screwed to said stud, and means on said another member to engage a keeper on a doorjamb for the door to which said handle is fastened.

7. The combination of claim 4, said handle comprising a handgrip portion having integral arms at its upper and lower ends, said arms having coplanar surfaces to contact the door to which the handle is fastened by said fastening means, and one of said arms having a through opening receiving said cylinder.

8. The combination of claim 7, said means to fasten said handle on a door comprising means extending through said arms.

9. The combination of claim 7, a doorjamb for said door, a keeper fixed to said doorjamb, and adapted to be engaged by said locking means.
